UNITED STATES PATENT OFFICE.

ARTHUR KREBS, OF PARIS, FRANCE, ASSIGNOR TO SOCIÉTÉ ANONYME DES ANCIENS ETABLISSEMENTS PANHARD ET LEVASSOR, OF PARIS, FRANCE.

FUEL-GOVERNOR FOR OIL-ENGINES.

SPECIFICATION forming part of Letters Patent No. 734,421, dated July 21, 1903.

Application filed November 10, 1902. Serial No. 130,800. (No model.)

To all whom it may concern.

Be it known that I, ARTHUR KREBS, engineer, a citizen of the French Republic, residing at 19 Avenue d'Ivry, Paris, France, have 5 invented certain new and useful Improvements in Fuel-Governors for Oil-Engines, of which the following is a specification.

This invention relates to fuel-governors for oil-engines and has for its object to insure 10 that the composition of the combustible mixture supplied to the cylinder shall be constant, which is necessary in order to insure the proper working of the engine whatever may be its speed or the power exerted by it. The 15 arrangement mostly used hitherto has an injecting-nozzle and a constant oil-level and is so adjusted as to insure a given supply corresponding to given conditions; but under this arrangement it is necessary for the 20 proper working of the engine to depart from this when, for instance, in order to maintain a given speed it becomes necessary to exert power proportional to the resistance to be overcome. Under such conditions the number 25 of strokes is constant, but the power given thereby is a variable one. If the air-inlet openings, the outlet for the explosive mixture to the engine-cylinder, and the level of the oil below the outlet of the injecting-nozzle be unchanged, then as the suction varies the composition of the combustible mixture will also vary. In order to insure constancy of the proportions of the combustible mixture, it will therefore be necessary to vary 30 one of the aforesaid conditions as the suction varies. In arrangements according to this invention the admission of air is varied. Hitherto this result was obtained by devices working independently of the engine and adjusted by trial by the driver, to whose judgment has been left entirely the proper setting of such devices, and the devices in question have not been satisfactory in operation. In 35 the arrangements in accordance with the present invention the air-supply is regulated automatically according to the amount of suction, a supplemental air-inlet, supplying ad-

ditional air according to requirements by causing the engine to vary the sectional area of the supplemental air-inlet, so that the 50 amount of air necessary to keep the composition of the explosive mixture constant is supplied as hereinafter explained.

The following description will clearly explain this invention with reference to the accompanying drawings, of which—

Figure 1 shows a section of the apparatus with the supplemental air-inlet closed and the outlet for the explosive mixture nearly closed. Fig. 2 is a similar view of the apparatus, the 60 supplemental air-inlet and the outlet for the mixture being open.

The apparatus consists of three principal parts. The first part comprises the main air-inlet, consisting of a pipe *a*, communicating 65 at one end with the atmosphere through an elbow *b* and at the other end with the atomizing-chamber *c*. Into this air-inlet pipe opens an injecting-nozzle *d*, the lower end of which communicates with a chamber *e*, connected to the oil-reservoir, (not shown in the drawings,) so that the level of the oil in the nozzle is kept constantly a little below its aperture.

The second part of the invention relates to 75 the mechanism which controls the admission of combustible mixture to the engine and comprises a hollow valve *f*, sliding easily in a chamber *g*, communicating with the atomizing-chamber *c* and closed at the other end. The 80 said hollow valve is provided with a stem *h*, connected to the engine-governor, and the chamber *g* is provided with a peripheral port *i*, communicating with the exhaust-pipe *j*, by which the combustible mixture passes to the 85 engine-cylinder. The periphery of the said hollow valve *f* preferably has triangular openings, so that the combustible mixture is gradually throttled when the said hollow valve approaches the end of its outward stroke. 90

The third part of the invention relates to the mechanism which constitutes the automatic regulating device and comprises supplemental air-inlets *m*, which may be situated

at any part of the apparatus provided they communicate with the atomizing-chamber *c* or the chamber *g*, containing the aforesaid hollow valve. A hollow piston *k* slides easily in a chamber *l*, communicating with the atomizing-chamber *c*, so as to control the air-inlet orifices *m* in the chamber *l*, in which it moves. The said hollow piston *k* is connected by a stem *n* to a regulating-head *p*, moving freely in a large chamber *o*, the joint between the said regulating-head and its chamber being made by an elastic and impervious diaphragm *q*, connected with the said regulating-head and chamber. The regulating-head moves in its chamber without friction in consequence of its being connected by the aforesaid diaphragm. A spring *r* normally forces the said regulating-head against the outer end of its chamber. One side of the regulating-head communicates with the atmosphere through a hole *s*, provided in the outer end of the chamber, this hole being of a small diameter in order to prevent the vibrations of the piston. When the regulating-head, controlled by the suction of the engine, is forced by the spring against the outer end of its chamber, the hollow piston *k*, connected with it, closes the aforesaid supplemental air-inlets *m*.

The operation of the apparatus is as follows: When the engine is at work, its speed is governed by the position of the hollow valve *f*, connected with the governor, which controls the passage *i* for combustible mixture through the said valve. When the engine is running at a low speed, the combustible mixture passes to the engine-cylinder through the triangular openings, Fig. 1, of the said hollow valve and the suction-stroke of the engine-piston tends to create a vacuum in the atomizing-chamber, whereupon air will be caused to enter through the normal or main air-inlet *a* and oil to issue from the nozzle *d*, opening into the said inlet. The regulating-head *p*, which communicates on one side with the atomizing-chamber through the hollow piston attached to it, is also acted upon by the suction in the atomizing-chamber, and when the engine runs at a higher speed, which corresponds to the admission of a larger quantity of combustible mixture to the cylinder, the hollow valve *f* uncovers the passage for combustible mixture through the hollow valve to a larger extent. An increase in the suction causes the regulating-head *p* to further compress its spring *r* and the hollow piston attached thereto to move, so as to uncover more or less the supplemental air-inlets *m* in the chamber surrounding this hollow piston, so that an additional quantity of air (depending upon the area of these openings and the suction beneath the regulating-head) enters the atomizing-chamber *c* and mixes with the mixture issuing from the main inlet-pipe, so that the proportion of air

to oil drawn in by the engine is automatically kept constant.

The section of the main air-inlet *a* and the initial pressure exerted on the regulating-head by the spring *r* are calculated in such a manner that the suction in the atomizing-chamber *c*, caused by the unloaded engine running at its lowest speed, does not cause the inlets for additional air to be uncovered. 70

Having now particularly described and ascertained the nature of my invention, and in what manner the same is to be performed, I declare that what I claim is—

1. A device of the class described embodying a main air-supply, fuel-injecting means coacting therewith, an atomizing-chamber, an exhaust-conduit, means actuated by the engine-governor to control the passage of the explosive from the atomizing-chamber to the conduit, and a supplemental air-supply controlled by the suction-stroke of the engine. 80

2. A device of the class described embodying a main air-supply, fuel-injecting means coacting therewith, an atomizing-chamber, an exhaust-conduit, a valve actuated by the engine-governor to control the passage of the explosive from the atomizing-chamber to the conduit, and a supplemental air-supply controlled by the suction-stroke of the engine. 90

3. A device of the class described embodying a main air-supply, fuel-injecting means coacting therewith, an atomizing-chamber, an exhaust-conduit, a valve provided with a notched periphery and actuated by the engine-governor to control the passage of the explosive from the atomizing-chamber to the conduit, and a supplemental air-supply controlled by the suction-stroke of the engine. 100

4. A device of the class described embodying a main air-supply, fuel-injecting means coacting therewith, an atomizing-chamber, an exhaust-conduit, a hollow valve actuated by the engine-governor to control the passage of the explosive from the atomizing-chamber to the conduit, and a hollow piston controlled by the suction-stroke of the engine and controlling supplemental air-supply inlets. 105

5. A device of the class described embodying a main air-supply, fuel-injecting means coacting therewith, an atomizing-chamber, an exhaust-conduit, a hollow valve having a notched periphery and actuated by the engine-governor to control the passage of the explosive from the atomizing-chamber to the conduit, a regulating-head controlled by the suction of the engine having a hollow piston operatively connected therewith, and supplemental air-inlets controlled by the piston. 115

6. A device of the class described embodying a main air-supply, fuel-injecting means coacting therewith, an atomizing-chamber, an exhaust-conduit, a hollow valve having a notched periphery and actuated by the engine-governor to control the passage of the explosive from the atomizing-chamber to the con- 120

duit, a regulating-head controlled by the suction of the engine and embodying a chamber, a movable plate and diaphragm arranged in the chamber, and a spring-controlled piston 5 operatively connected with the diaphragm to control supplemental air-inlets.

In testimony whereof I have hereunto set

my hand in presence of two subscribing witnesses.

ARTHUR KREBS.
